AIR GUN

Walter R. Benjamin, Granite City, Ill.

Application June 12, 1942, Serial No. 446,835

5 Claims. (Cl. 124—13)

This invention relates generally to improvements in air rifles and pistols, and has for a principal object to provide a novel construction in which barrels having different bore diameters may be employed selectively for firing shot of different sizes.

Another object of the invention is to provide an air gun wherein the admission valve through which air is forced under pressure into the pressure chamber is designed and arranged for easy removal and replacement through the barrel in which the piston for the development of air pressure is mounted.

A further object of the invention is to provide an air gun having a fixed barrel of large diameter and an auxiliary barrel of smaller diameter which is designed to be introduced into the fixed or larger barrel for use in firing small diameter shot, with novel means for maintaining the auxiliary barrel in inoperative position adjacent the fixed barrel or within the fixed barrel for use, as desired.

Still another object of the invention is to provide a dual barrel air gun of the character stated in which means is provided for preventing small shot from getting into the air release valve mechanism in the event that such shot is inadvertently introduced into the larger barrel.

Still another object of the invention is to provide a novel air release valve by which the admission of air under pressure from the air pressure chamber into the shot barrel is facilitated upon the pulling of the gun trigger.

The invention will be best understood from a consideration of the following detailed description taken in connection with the accompanying drawing, it being understood, however, that the invention is not to be considered as limited by the specific illustration or description but that such illustration and description constitute a preferred embodiment of the invention.

In the drawing:

Figure 1 is a view in top plan of the barrel and forward end of the stock of a rifle constructed in accordance with the present invention.

Figure 2 is a view in side elevation of the structure shown in Figure 1, parts being broken away.

Figure 3 is a longitudinal sectional view through the gun barrel and piston cylinder, the structure being shortened by breaking out the central portion, and showing the air pressure chamber and mechanism for the admission thereto and release therefrom of air under pressure.

Figure 4 is a sectional view taken substantially on the line 4—4 of Figure 3.

Figure 5 is a longitudinal section corresponding with Figure 3 but showing the auxiliary or removable smaller barrel in the larger barrel for the firing of small diameter shot.

Figure 6 is a detail view of the inner end of the auxiliary barrel showing its construction for use as a valve removing tool.

Referring now more particularly to the drawing, the numeral 10 generally designates the stock of the gun as constructed in the form of a rifle, the butt end of the stock not being shown. The handgrip portion of the stock is indicated at 11 while the forward end thereof is indicated by the numeral 12. This forward end of the stock is provided upon its top edge with a suitable groove or channel 13 in which rests the rear or breech end of a cylinder 14, which carries a tapped stud 15 which extends into a suitable recess in the forward end 12 of the gun stock to receive the securing screw 16 which is extended through the forward end of the stock from the under edge, as shown in Figure 2, whereby the cylinder and the hereinafter described barrel and other parts carried thereby, are maintained in proper position upon the stock.

While the invention is illustrated and described as applied to a rifle, it will be readily apparent to those versed in the art that the invention may be readily used in a gun constructed as a pistol, and it is, therefore, to be understood that in referring broadly to a gun in the specification and claims a pistol type of construction is meant as well as a rifle.

Upon the top of the cylinder 14 and extending longitudinally thereof, is the shot or bullet barrel 17 the rear end of which is closed, as indicated at 18, while just forwardly of the rear end the interior diameter of the barrel is reduced or constricted, as indicated at 19 and as particularly described and claimed in my prior Patent No. 2,117,935 of May 17, 1938. This constriction as illustrated assures the maintenance in position 40 in the valve of the lead pellet or shot 20 which will become jammed or frictionally secured in the constricted area when dropped into the muzzle end of the barrel.

Extending transversely of the barrel 17 at the rear of the constricted portion 19 is a pin 21 which functions to prevent smaller shot passing beyond the constricted portion in the event that such shot is inadvertently dropped into the barrel.

Between the constricted portion of the barrel 55 or between the pin 21 and the closed rear end 18

the barrel is provided with an air admission opening 22 which coincides with an opening 23 formed through the wall of the cylinder 14. Upon the inner side of the cylinder concentric with the opening 23 is fixed the short tube 24 which extends radially inwardly a short distance, preferably less than half the inside radius of the cylinder, and this tube forms a part of the compressed air release valve unit hereinafter more completely described.

The rear or breech end of the cylinder 14 is closed by a plug 25, preferably of rubber, backed up by a plate or disk 26 which is secured in position by the retaining ring 27 which in turn is held in place by the screw 28 which is passed through the wall of the cylinder.

This plug or closure wall 25 is disposed rearwardly of the tube 24 and fixed in the cylinder 14 upon the forward side of the tube 24 is the partitioning disk 29 which is provided with a central threaded opening in which is threadably secured an end of the sleeve or jacket portion 30 of a valve unit which is indicated as a whole by the numeral 31. This sleeve 30 has removably secured therein the valve inside 32 which is of the same construction as the well-known Schreeder valve used in the inner tubes for motor vehicle tires. No detailed illustration of this valve is given or believed to be necessary in view of its well-known construction. It will be noted, however, that the valve unit is mounted in the partition 29 so that the inside piece 32 may be readily withdrawn by the introduction of a suitable implement through the muzzle end of the cylinder 14. Thus, the valve piece can be moved for cleaning or replacement when necessary.

Fixed to the sleeve 30 of the valve unit 31 is a resilient arm 33 which extends longitudinally of the chamber 34 which is formed between the partition 29 and the plug 25 and terminates in the upturned finger 35 which is directed toward the inner end of the tube 24 upon the axial center thereof. Upon this upturned finger 35 of the resilient arm 33 is balanced a disk body 36 which has a covering upon its top face of rubber or other suitable material, indicated by the numeral 37. This disk and covering form the movable element of the compressed air outlet or exhaust valve of which the tube 24 forms a fixed part, and the spring arm presses the resilient covering 37 against the lower end of the tube so as to effectively close the latter.

Extending through the rear end of the barrel 17 and through the tube 24 is a trigger pin 38 which rests at its inner end upon the movable element of the exhaust valve and at its outer end projects a substantial distance beyond the top of the gun barrel 17. This trigger pin is freely movable through the barrel so that when it is pressed inwardly it will shift the movable portion of the exhaust valve against the tension of the spring 33 and thus open the inner end of the tube 24.

The forward end of the handgrip portion of the stock is provided with a slot extending from the bottom edge to and through the upper edge, as indicated at 39, through which extends a trigger arm 40, the lower end of which projects beyond the lower edge of the stock and is covered by the guard 41 while the upper end is suitably shaped to extend upwardly across the rear or breech end of the cylinder 14 where it is joined to an angularly extending finger 42 which is pivotally attached, as at 43, to the top of the cylinder and extends forwardly over and engages the upper end of the trigger pin 38. The trigger finger is

here illustrated as being maintained in position upon the upper end of the trigger pin 38 by gravity, but it will be readily apparent that, if found desirable, a light spring may be suitably employed for maintaining the trigger lightly in contact with the trigger pin.

The numeral 44 designates a piston which is introduced into the forward end of the cylinder 14 and which carries upon its inner end the cup 10 or packing 45 which is maintained in place by washer 46, preferably of leather, and the screw 47 which extends into the end of the piston which may be made of wood or any other suitable material.

The piston 44 is provided with the longitudinal slots 48 through which extends a movement limiting pin 49 which is secured across the muzzle end of the cylinder 14. Thus, the inward and outward movements of the piston are limited so that it cannot be withdrawn entirely from the cylinder and, on the other hand, it cannot be forced inwardly to an extent to push against the partition 29.

The numeral 50 designates an auxiliary barrel which has an overall diameter slightly less than the interior diameter of the fixed barrel 17 so that the auxiliary barrel may be extended into the fixed barrel and have snug engagement therein. This auxiliary barrel is designed to shoot a pellet 51 of materially smaller diameter than the pellet or shot 20 and, as is shown in Figure 5, the inner end of the auxiliary barrel is constricted, as indicated at 52, so that when the auxiliary barrel is in position in the main or fixed barrel and the pellet or shot 51 is dropped into the auxiliary barrel it will enter the constricted portion 52 and be secured against accidental discharge.

Upon one side of the main or fixed barrel 17 there are secured the guides 53 which are aligned longitudinally of the barrel and which are designed to have the auxiliary barrel extended therethrough so as to support this barrel in position ready for use during such time as the main or fixed barrel is being used.

In order to maintain the auxiliary barrel 50 in position in its supporting guides the forward end of the auxiliary barrel has secured thereto a ring or eye 54 and this eye is engaged by one hooked end 55 of a spring 56, the other end of which spring is fixed to the cylinder 14, as indicated at 57. This spring 56 also functions to retain the auxiliary barrel in position in the main barrel when the auxiliary barrel is so placed for use. Thus, it will be seen that the spring 56 performs the two-fold function of securing the auxiliary barrel against accidental displacement from the carrier guides 53 and for securing it against accidental displacement or discharge from the main barrel 17 when it is being used for shooting small shot or pellets.

The eye or ring 54 also performs the function of limiting the movement of the auxiliary barrel into the fixed barrel 17, as shown in Figure 5.

In the use of the gun air pressure is built up in the chamber 34 by repeated reciprocation of the piston 44 in the cylinder, the air being forced through the valve unit 31 into the chamber 34. When the desired pressure has been built up and a pellet or shot has been dropped into the selected barrel, as shown either in Figure 3, or in Figure 5, it may be forcibly discharged by pulling back on the trigger 40, thereby unseating the valve element 36 from the end of the tube 34. This permits the air under pressure to rush into

the breech end of the barrel and forcibly dislodge the bullet from the constricted end of the barrel in which it is lodged so that it will be discharged from the breech end with great force.

If desired, a number of pellets may be introduced into either of the barrels or a large pellet may be introduced into the barrel 17 followed by a number of smaller pellets, thereby converting the rifle into a shotgun.

As previously stated, by providing the pin 21 across the rear end of the larger barrel 17 the accidental introduction of small pellets into the tube 24 of the air discharge valve is prevented.

While the element 36 of the air discharge valve has been shown as having a depression in its under side into which the spring finger 35 engages, this construction may be reversed if found desirable by providing the valve element 36 with a pin and the spring arm 33 with an aperture in which the pin may engage. In either case, the valve element 36 would be supported relatively loosely so that it may readily adjust itself to the angle of the lower or inner end edge of the tube 34 and thus establish an air-tight contact therewith.

The inner or auxiliary barrel 50 may be suitably formed so that it may be used, when required, for the removal or replacement of the valve unit 32. To this end the breech end of the auxiliary barrel is provided with the transverse slot 58 in which may be engaged the bar-like forward end portion 59 of the valve unit 32 so that the necessary rotary movement may be given the unit to effect its removal or placement in the sleeve portion 30. It will be understood, of course, as previously stated, that to carry out this operation the piston retaining pin 49 is removed and the piston withdrawn from the cylinder 41, after which the auxiliary barrel may be conveniently introduced into the cylinder.

I claim:

1. In an air gun, a shot receiving barrel, means for introducing air under pressure into the breech end of the barrel, an auxiliary shot receiving barrel designed to be introduced into the first barrel, means at one side of the first barrel for receiving the auxiliary barrel to support the same when not in use, and means for operatively coupling the muzzle end of the auxiliary barrel with the first-mentioned barrel when the auxiliary barrel is in either the supporting means or in the first-mentioned barrel to maintain the auxiliary barrel against accidental displacement.

2. A gun structure as set forth in claim 1, in which said means for securing the auxiliary barrel comprises a spring operatively coupled at one end with the first-mentioned barrel, an eye carried by the auxiliary barrel adjacent the muzzle end, and a hook at the other end of the spring for engaging said eye.

3. In an air gun, a body forming a holding means for the gun, a cylinder supported upon the body and closed at the breech end, a barrel disposed upon the top of and longitudinally of the cylinder, a partition means within the cylinder in spaced relation with the closed end thereof of providing a compressed air chamber, an inlet valve comprising a sleeve portion extending through the partition into the compression chamber and a removable inside unit closing the sleeve, said inside unit functioning to admit air from the forward part of the partition into the cham-

ber and having a wrench bar across the end remote from the chamber, an outlet valve controlled passage leading from the chamber into the breech end of the barrel, trigger means for effecting the opening of the outlet valve, a piston reciprocably mounted in the forward part of the cylinder for forcing air through the inlet valve into the air chamber, and an auxiliary barrel adapted to be inserted into the first barrel, said auxiliary barrel having one end slotted for engagement with the bar portion of said valve unit to facilitate the removal of said unit through the forward end of the piston cylinder.

4. An air gun comprising a handgrip portion, a cylinder supported on and secured to said portion, said cylinder being closed at the breech end, a partitioning means within the cylinder in spaced relation with the breech end and forming therewith a compressed air chamber, an air inlet valve in said partitioning means opening into the chamber, a piston reciprocable in the forward end of the cylinder for introducing air through said valve into the chamber, a gun barrel supported upon the top of and extending longitudinally of the cylinder, an air transfer passage leading from said chamber into the gun barrel at the breech end of the latter, the breech end of the gun barrel being closed and the gun barrel being interiorly constricted adjacent the breech end and forwardly of the air inlet means, valve means for controlling the escape of air from the chamber into the gun barrel, trigger mechanism for effecting the opening of said valve means, an auxiliary gun barrel adapted to be inserted into the first gun barrel from the muzzle end thereof, means adjacent the first gun barrel for receiving and supporting the auxiliary barrel, and means for detachably coupling the muzzle end of the auxiliary barrel with the fixed barrel to hold the auxiliary barrel in either the supporting means therefor or in the fixed barrel.

5. An air gun comprising a handgrip portion, a cylinder supported on and secured to said portion, said cylinder being closed at the breech end, a partitioning means within the cylinder in spaced relation with the breech end and forming therewith a compressed air chamber, an air inlet valve in said partitioning means opening into the chamber, a piston reciprocable in the forward end of the cylinder for introducing air through said valve into the chamber, a gun barrel supported upon the top of and extending longitudinally of the cylinder, an air transfer passage leading from said chamber into the gun barrel at the breech end of the latter, the breech end of the gun barrel being closed and the gun barrel being interiorly constricted adjacent the breech end and forwardly of the air inlet means, valve means for controlling the escape of air from the chamber into the gun barrel, trigger mechanism for effecting the opening of said valve means, an auxiliary gun barrel adapted to be inserted into the first gun barrel from the muzzle end thereof, a contractile spring secured at one end to the cylinder, an eye carried by the auxiliary barrel adjacent the muzzle end thereof, and means for coupling the other end of the spring with said eye whereby the spring operates to maintain the auxiliary barrel either in the supporting means or in the fixed barrel.
